BLADE ADJUSTMENT FOR WOOD PLANERS

Rudolph Müller, Elizabeth, N. J.

Application May 31, 1941, Serial No. 395,898

1 Claim. (Cl. 145—11)

My invention relates to means for adjusting the cutting bit in wood planers.

The well known difficulties in the existing means occur when the operator must cease work and with some difficulty adjust the bit to a particular extension before each piece is planed.

I have found by experience that the loss of time thus caused is a large proportion of the total time used by an operator.

It is clear that the more numerous the jobs are in a day, the more often an artisan is required to adjust the bit of his plane hence, the more hours of work lost in mere routine mechanical adjustment that heretofore could not be avoided.

Those skilled in the art have frequently experienced the problem of a "high spot" in a piece being planed. In order to cut off the "high spot" and not affect other work on the piece the operator must cease work, adjust his bit and then after removing the "high spot" cease work again and re-adjust his bit to proceed with the job.

Again it is a frequent occurrence to find a "low spot" in a piece being worked. The same loss of time occurs when the adjustments requisite are effected.

The principal object of my invention is to provide a construction which will permit the adjusting of the bit with the plane in its working position on the work and the operator's hand holding the plane in its normal position while working.

My means of accomplishing the foregoing objects may be more readily understood by having reference to the accompanying drawing which is hereunto annexed and made a part of this specification in which:

Fig. 1 is a vertical sectional elevation showing the interior construction;

Fig. 2 is a section taken on the line 2—2 in Fig. 1; and

Fig. 3 is a fragmentary detail view showing the modified form of construction.

Similar reference numerals refer to similar parts throughout the entire specification.

As shown in the drawing the body 1, of the plane is provided with hand grips 2 and 3 adjacent each end. The rear grip being formed by shaping the body of the plane. Between the grips 2 and 3 is a slot in which is mounted the plane iron or bit 4, which rests upon an inclined surface 5, upon which the plane bit 4 slides when the adjustment is being made. A break or chip iron 6 is mounted on the bit in the usual manner and secured thereto, as shown it is fastened with a screw.

5 A clamping plate 7 is mounted on the break iron and is held in position by means of a key-hole slot 8, in which is mounted a screw 9 which is screwed into the body of the plane. Means to adjust the clamping plate 7, consists of an adjusting screw 10. An adjusting lever 11 by means of which the cutting edge of the plane iron or bit 4 may be adjusted, all of these parts are of more or less standard practice, well understood by those skilled in the art so that a detail description is not deemed necessary. As pointed out in the preamble it is desirable to provide means for manually varying the extent of the projection of the cutting edge of the plane iron or bit in relation to the bottom of the plane body.

10 One means by which I accomplish this is clearly shown in Figs. 1 and 2 which shows a compartment formed in the body of the plane adjacent but below the inclined surface 5 upon which slides the bit 4.

15 In this compartment it will be seen I provide an arm 12 which is pivotally mounted upon pin 13. The arm 12 is provided at its upper end with a lug 14 which extends into a slot 15 provided in the break iron 6 for its reception. The other end of the arm is bifurcated, the prongs 16 and 17 engaging a crank arm 18 which is fixedly mounted on a toothed wheel 19. This wheel is 20 rotatable upon an axle 20 mounted in any suitable or convenient manner in the body 1 of the plane as shown in Fig. 2 a metal wall is mounted abutting the rear wall of the compartment to which the axle 20 is fastened. It will be obvious 25 that rotation of the wheel 19 will carry with it the crank arm 18 this in turn will cause the lug 14 to abut the edges of the slot 15 move the bit 4 in or out of the body 1 of the plane in accordance with the direction of rotation of the wheel.

30 My means of rotating the wheel 19 comprises a pinion 21 which is very much smaller than the gear wheel 19 thereby affording an exceedingly minute adjustment of the cutting edge of the bit carried by a shaft 22 which may be journaled in a plate 23. A collar 24 mounted on the shaft 22 serves to hold the pinion 21 in mesh with the teeth on the wheel 19. The plate 23 may be secured to the body 1 of the plane by screws 25 or in any other desired manner and closes the opening into the compartment.

35 Upon the end of the shaft 22 I mount a disk 26 the periphery of which is preferably knurled so as to provide a convenient gripping surface for the user's finger to rotate the disk 26. The 40 rotation of which will move the pinion 21, which

will in turn move the wheel 19 in either a clockwise or counterclockwise direction and in that manner advance or retract the break iron 6, which being fastened to the bit, will project or withdraw the cutting edge of the bit 4 through the coaction of the crank arm 18 and the lug 14 on the pivoted arm 12.

It will be obvious from the foregoing description, that by the use of this means of adjusting the position of the cutting edge of the bit 4 the varying conditions above referred to in the work can be met without the slightest loss of time to adjust the position of the bit 4.

In Fig. 3, I have shown a preferred form in which I have substituted for the pivoted arm 12, a linkage consisting of a pair of links 30 and 31, the inner ends of which are pivotally attached, the link 30 has a lug 32 which is adapted to fit in the slot 15 in the same manner as the lug 14 on the pivoted arm 12. The end 33 of link 31 is secured to the crank arm 18, thus it will be seen that if the wheel 19 is oscillated the links will be shifted and the lug 32 will move the bit 4 inwardly or outwardly as the case may be. Although I have described with some degree of particularity the specific construction of the two forms of my improvement, it is to be understood that this is only for the purpose of disclosing constructions which I have found in practice to be very satisfactory, and I do not wish to be understood as limiting myself thereby except as such limitations may appear in the hereinafter appended claim.

Having described my invention what I regard as new and desire to secure by Letters Patent is:

In a plane, a plane body the rear end of which extends upwardly to form a hand grip said body having a bit slot therein provided with an inclined surface, and an opening in the side of the plane body leading to a compartment beneath the inclined surface and adjacent thereto, a bit mounted in said slot upon said inclined surface and a break iron secured to said bit, there being a slot in said break iron; an axle secured to the inner wall of said compartment, a gear wheel rotatably mounted thereon, a laterally extending pin eccentrically secured to said wheel, a pin fixedly mounted in said body adjacent the bit and extending parallel to said axle, a line one end of which extends into and abuts the end walls of the slot in the break iron, a second link one end of which is pivotally attached to the first named link, its other end rotatably engaging said pin, a plate which closes the opening to said compartment, a rotatable shaft journaled in said plate, a pinion which engages the teeth of said gear carried by said shaft, a knurled disk on the outer end of said shaft whereby the pinion and in turn the gear may be oscillated and the position of the break iron and bit shifted to adjusted position.

RUDOLPH MÜLLER.
